UNITED STATES PATENT OFFICE.

ERICH LANGGUTH, OF EUSKIRCHEN, GERMANY.

ELECTROMAGNETIC ORE-SEPARATOR.

SPECIFICATION forming part of Letters Patent No. 781,077, dated January 31, 1905.

Application filed February 1, 1904. Serial No. 191,539.

To all whom it may concern:

Be it known that I, ERICH LANGGUTH, engineer, a subject of the Emperor of Germany, residing at Koelnerstrasse 137, Euskirchen, 5 Prussia, Germany, have invented a certain new and useful Improvement in Electromagnetic Ore-Separators; and I do hereby declare the following to be a full, clear, and exact description of the invention, such as will enable others skilled in the art to which it appertains to make and use the same.

My invention relates to apparatus for separating magnetic particles from ores, more particularly iron ores that have been reduced by 15 grinding or crushing to a state resembling sand.

More especially my improved apparatus relates to dynamo-electric machines or electro-motors as applied for the purposes of magnetic ore separation.

The invention consists in providing the armature of a dynamo-electric machine or electromotor with a casing or jacket of magnetic material, preferably iron, for the purpose of 25 protecting the armature-windings against the mechanical action of the ore and at the same time of increasing the density of the magnetic field employed.

Of the accompanying drawings, Figures 1 and 2 are a longitudinal and a cross section, respectively, of an armature constructed according to my present invention. Figs. 3 to 35 6 are longitudinal and cross sections of modifications. Fig. 7 is a section showing the preferred shape and disposition of the field-magnets in connection with the armature, and Figs. 8 and 9 illustrate a modification.

In the drawings, *a* is the active armature-iron, preferably composed of a number of 40 disks placed face to face in the usual manner and insulated from each other by paper or other suitable means. The single disks are punched at the edges, so as to form longitudinal grooves on the exterior surface of the 45 armature, as is usual in the manufacture of dynamo-machines. The surface thus produced is, however, ill-suited for the purpose of separation, partly because it is too rough and partly because the insulated wires constituting the armature-windings would soon be destroyed by

the mechanical action of the ore if it were allowed to pass over them. Previous inventors have tried to obviate this difficulty by protecting the exterior surface of the armature by means of a cloth covering. This plan, however, 55 has the great disadvantage that though a mechanical protection may be obtained the field is at the same time considerably weakened, because sufficient space has to be provided between the field-magnets and the circumference 60 of the armature to admit the cloth. According to my invention I obtain the same or even a better protection for the armature-windings without weakening the field by providing an iron covering enveloping the armature. In 65 the drawings this covering or jacket is designated by the letter *b*. It may consist of ring-shaped disks punched so as to admit of their being drawn over the armature after the winding has been completed, as is shown in Figs. 70 1 and 2, or else of iron wires *c*, Figs. 3 and 4, wound onto the armature. Figs. 5 and 6 show the iron covering *b*, consisting of ring-shaped disks, applied to a ring armature *d* of the usual construction. The armature thus obtained is mounted between the usual field-magnets, preferably disposed in an oblique 75 position, and made in a special shape for the purpose of guiding the ore into the magnetic gap. Thus in Fig. 7, *a* is the armature, and *e* and *f* the field-magnets. As shown in the drawings, the pole-piece *f* is cut away so as to present a convex surface to the armature, thus forming a gradually-narrowing gap for the admission of the ore and at the same time 80 concentrating the lines of force at one single line. The ore glides downward over a sloping surface and passes through the gap. The magnetic material is retained for a longer period than the non-magnetic or only partially-magnetic material, and thus a separation takes 85 place, as is usual in the art.

Figs. 8 and 9 show a modification of the arrangement. The armature *d* is mounted on a vertical shaft and rotated, as usual, between 90 the pole-pieces *S* and *N*, and the ore-dust is admitted to the magnetic gap by means of a suitably-sized funnel placed above the armature. It passes through the gap and is separated by the attraction of the armature, by 95 100

which the magnetic parts are carried round a longer part of the circumference than the non or less magnetic parts.

The use of the armature of a dynamo-machine as a separating magnetic body has the great advantage that no special arrangements are wanted for driving it. The brushes are simply connected to a source of electrical current, and the armature can thus be rotated at 10 any speed desirable with an exceedingly small expenditure of energy. At the same time my magnetic covering *b* forms an effectual protection of the armature-windings against the deteriorating action of the ore and increases 15 rather than weakens the field in the magnetic gap.

Having now particularly described and ascertained the nature of my said invention and the manner in which the same is to be performed, I declare that what I claim is—

1. In a magnetic separator, the combination with pole-pieces, of an armature rotating between said pole-pieces and having windings, a shield of magnetic material mounted directly 25 on said armature and rotating therewith, means for feeding the material to be separated to said armature, and means for collecting the separated material.

2. In a magnetic separator, the combination 30 with pole-pieces, of an armature rotating between said pole-pieces and having windings, a shield rotating with said armature and consisting of annular members of magnetic material mounted directly on said armature, 35 means for feeding the material to be separated to said armature, and means for collecting the separated material.

3. In a magnetic separator, the combination 40 with pole-pieces, of an armature rotating between said pole-pieces and provided with windings, said parts being arranged to produce a gradually-narrowing gap, means for feeding the material to be separated to said gap, and means for collecting the separated material.

4. In a magnetic separator, the combination 45 with pole-pieces, of an armature rotating between said pole-pieces and provided with windings, said parts arranged to produce a gradually-narrowing magnetic gap, a covering of magnetic material for said armature, means 50 for feeding the material to be separated to said gap, and means for collecting the separated material.

5. In a magnetic separator, the combination 55 with an armature provided with windings, of pole-pieces, one of said pole-pieces being convex whereby a gradually-narrowing magnetic gap is formed between said pole-pieces and armature, means for feeding the material to be separated to said gap, and means for collecting 60 the separated material.

6. In a magnetic separator, the combination 65 with an armature provided with windings, of a covering of magnetic material for such armature, pole-pieces, one of said pole-pieces being convex, whereby a gradually-narrowing magnetic gap is formed between said pole-pieces and armature, means for feeding the material to be separated to said gap, and means for collecting 70 separated material.

7. In a magnetic separator, the combination 75 with an armature provided with windings, of a shield composed of annular members of magnetic material mounted directly on said armature, a pair of pole-pieces disposed in an oblique position, one of said pole-pieces being convex whereby a gradually-narrowing magnetic gap is formed, means for feeding the material to be separated to said gap, and means 80 for collecting the separated material.

In testimony whereof I have hereunto set my hand and affixed my seal in the presence of the two subscribing witnesses.

ERICH LANGGUTH. [L. S.]
